UNITED STATES PATENT OFFICE.

HENRY LUND SMITH, OF PATERSON, NEW JERSEY.

SHIELD.

1,419,322.

Specification of Letters Patent. Patented June 13, 1922.

Application filed February 4, 1921. Serial No. 442,443.

To all whom it may concern:

Be it known that I, HENRY LUND SMITH, a citizen of the United States, residing at Paterson in the county of Passaic and State 5 of New Jersey, have invented certain new and useful Improvements in Shields, of which the following is a specification.

This invention relates to shields and particularly to shields of the class set forth in 10 my applications for U. S. Letters Patent for vision shields, one bearing the Serial Number 411,724 and the other the Serial Number 440,866. The device herein shown and described is designed to provide a simpler and 15 less expensive and yet substantially as strong and durable a structure as that explained by way of example in the first of my two applications above named.

In the drawings,

20 Figure 1 is a rear elevation of the improved shield showing the same attached to a wind shield;

Figure 2 is a side elevation, the wind shield being shown in section on the line 25 2—2 in Figure 1;

Figure 3 shows a modified form of the device in side elevation and attached to a wind shield, which appears in vertical section;

30 Figure 4 is a sectional view on the line 4—4 of Figure 3; and

Figure 5 is a vertical sectional view of the device shown in Figure 3.

The shield proper herein shown is of the 35 inclined-vane type. In Figures 1 and 2 there are a plurality of upright holder members *a*, preferably three, equidistantly spaced from each other and having narrow inclined pockets *b* formed therein one above another, 40 the pockets in this instance extending inward from one edge of each holder member. The vanes *c* are fitted into these pockets so as to make a rigid substantial structure. In Figures 3 and 5 the construction is much 45 the same excepting that the holder members *a'* have the pockets *b'* in the form of elongated holes or slots, the ends of the vanes *c'* being reduced to fit such pockets. In both forms there is also a vane *d* which is fitted 50 into pockets *e* in the holder members at the ends thereof so as to stand in a plane at an angle to that of any one of the vanes *c* or *c'*, or substantially parallel with the length of the holder members. The front of the 55 shield is that corresponding to the lower edges of the vanes *c* or *c'*, and the plane in

which vane *d* lies is preferably offset toward the front or back of the shield proper according to whether the latter is to be attached to its supporting upright (to be described) back of or in front of the same (compare Figures 2 and 3). The present device is intended principally though not indispensably as means to protect the eyes of the driver of a road vehicle at night from 60 the glare of the lights of an approaching vehicle, and to this end the vanes *c* or *c'* are translucent, the intervening spaces affording clear-vision areas; the vane *d* is also preferably translucent and is supported when 65 used to be in about horizontal alinement with the driver's eyes, so that his distant vision is usually therethrough, and in the present case it forms means for attachment of the shield 70 proper to its supporting upright.

75 Said upright is indicated at *f*, being a tube with a knob *g* on its lower end. Telescoped into it is a stem *h* which depends from and is preferably pivoted at *i* to a suitable clip *j* which is in turn secured to 80 the wind-shield or some other fixed part *j'* of the vehicle.

A split clamp *k* is secured with its flat face *l* against the vane *d* by screws *m*, the split portion of the clamp embracing the upper end portion of the tubular upright *f*, which is also split, as at *n*, and having a binding screw *o*; when the screw *o* is properly adjusted it not only secures the upper portion of the shield to the upright but may 90 bind the latter with sufficient friction to the stem so that by means of the knob *g* the upright carrying the shield may at will be adjusted longitudinally of the stem but the upright will retain the position to which it 95 is thus adjusted.

To secure the lower end portion of the shield to the upright I provide a hook *p* which is penetrated by the upright and has its hook-portion hooked over one of the 100 vanes *c* or *c'*, as the lower one. It will strengthen the structure if this hook is bifurcated, as shown, and made to straddle the center holder member *a* or *a'*, opposite which the upright is arranged.

If the shield proper is placed forward of the upright the clamp *k* will be secured to the rear face of vane *d*; if the shield proper is placed back of the upright said clamp will be secured to the front face of the 110 vane *d*.

The material of the shield proper, and

particularly the vanes, may be glass; but I prefer that it be celluloid or some other infrangible material, in which case the described arrangement and construction of 5 the parts will be such as to produce a structure that is strong and durable and well adapted to withstand the effects of the handling to which the device is supposed to be subjected, as in adjusting longitudinally 10 of the stem member or on the pivot *i.*

Having thus fully described my invention, what I claim as new and desire to secure by Letters Patent is:—

1. In combination, with a shield including 15 shielding vanes rigidly held in planes at an angle to each other, an upright, and means to secure the shield to the upright with one vane substantially parallel therewith, said means engaging the latter vane.

20 2. In combination, with a shield including shielding vanes rigidly held in planes at an angle to each other, an upright, and separate means to secure the shield to the upright with one vane substantially parallel therewith, one of said means engaging the latter vane and the other the other vane.

25 3. In combination, with a shield including shielding vanes rigidly held in planes at an angle to each other, an upright, and means

to secure the shield to the upright with one 30 vane substantially parallel therewith including a clamp fixed to the latter vane and clamping the upright.

4. In combination, with a shield including 35 shielding vanes rigidly held in planes at an angle to each other, an upright, and means to secure the shield to the upright with one vane substantially parallel therewith including a hook extending from the upright and hooked around the other vane. 40

5. In combination, with a shield including 45 shielding vanes and a holding member in which they are rigidly held at an angle to each other, an upright, and means to secure the shield to the upright with one vane substantially parallel therewith including a hook extending from the upright and straddling the holder member and hooked around the other vane.

6. In combination, a supporting stem, an 50 upright having a contractible portion embracing the stem, a structure to be supported, and an adjustable clamp carrying said structure and embracing said contractible portion and holding the same in gripping 55 relation to the stem.

In testimony whereof I affix my signature.

HENRY LUND SMITH.
